MASK FOR FOWL

Hyman Nadler, Brooklyn, N. Y.

Application May 13, 1938, Serial No. 207,692

1 Claim. (CL 119—97)

This invention relates to devices adapted to be worn by fowl, and relates more particularly to a mask adapted to be attached to the beak of a fowl for the purpose of preventing the fowl from fighting, picking, pulling the feathers off, or otherwise injuring other fowl.

Poultrymen annually lose an appreciable number of fowl due to their tendency toward cannibalism, i. e., one or more fowl destroying another 10 fowl by picking the organs of the fowl through the vent when the vent has been caused to bleed due to the passing of an egg, for example. The red color of the blood attracts the other fowl which proceed to peck at the vent with the result 15 that the vital organs of the fowl are picked out causing the death of the fowl.

It is an object of this invention to provide an improved mask which may be readily applied to the beak of the fowl without causing injury to 20 the fowl and which does not interfere with the fowl's breathing, eating or drinking and yet prevent the fowl from injuring or pecking other fowl.

Another object of this invention is the provision 25 of a mask which is adapted to be attached to the beak of the fowl by a means passing through the nostrils of the fowl.

A further object of this invention is to provide 30 the mask with openings in which are mounted pieces of colored film or foil.

Other objects of this invention, together with 35 certain details of construction and combinations of parts, will be apparent from the following detailed description and will be pointed out in the appended claim.

In the drawing wherein the preferred embodiment 40 of my invention is shown,

Figure 1 is a side elevational view of the device 45 of the present invention showing the same mounted on the beak of the fowl.

Figure 2 is a side elevational view of the device 50 showing the position of the same when the head of the beak of the fowl touches the ground.

Figure 3 is a front elevational view of the device, and

Figure 4 is a plan view of the blank from 55 which the device of the present invention is formed.

Like reference numerals designate like parts throughout the several views of the drawing.

Referring first to Figure 4 of the drawing, there 60 is shown a blank generally indicated by reference numeral 5 which is cut from a flat sheet of metal. Although any suitable metal may be employed, I prefer to make the mask from sheet aluminum.

The blank 5 is provided with a recess 6 forming

two substantial extensions 7 in which are openings 8. The inner peripheries of openings 8 are notched to form prongs 9. The blank is also provided with pin holes 11 and a small extension 12.

In forming the blank 5 into the mask as shown in Figure 3, it is bent first along a line bisecting the base 13 of extension 12 to form a rounded portion 14 adapted to rest on the beak of the fowl and leg portions 15 adapted to extend along the side of the beak, as shown in Figure 1. The extensions 7 are then bent along the dotted lines 16 shown in Figure 4, forming an angle of approximately 45° with the plane of the blank 5.

Fowl, as stated above, have cannibalistic tendencies and are especially attracted by the red 15 color of blood causing them to peck at a wound, a bloody vent, or at any part of the fowl when red blood is visible. This pecking often results in the death of the fowl being pecked. To this end, I provide the openings 8 with circular eye 20 pieces 17 of transparent colored film, foil or glass which are adapted to be held in position by means of prongs 9. The eye pieces may be of any color which would offset the red of the blood, etc., I prefer, however, to use red eye-pieces since 25 this color would tend to make the fowl accustomed to see red at all times and therefore would make this color lose its attraction to the fowl. After wearing the device of my invention with its red eye pieces, I have found that if the fowl 30 lost its mask it did not attempt to peck at red colored objects.

The mask is adapted to be held in position on the beak of the fowl by means of a pin, preferably a cotter-pin, 18, which extends through 35 holes 11 and the nostrils of the fowl.

The mask is so constructed that it rests directly on the beak of the fowl when the head of the fowl is raised, i. e. when it is not feeding. When the head of the fowl is lowered for the 40 purpose of feeding as shown in Figure 2, a projection 19, formed from the extension 12 on the blank, first touches the ground or feeding trough causing the mask to raise itself about the pin 18, thus permitting the fowl to gain access to the 45 feed and simultaneously lowering the eye pieces out of the vision of the fowl. This extension also is an additional protective element as it is directly in front of the tip of the beak.

It will thus be seen that I have provided a mask 50 which effectively protects fowl from injury by other fowl and which is durable in use and inexpensive in cost. The mask of my invention has been formed to have no ill effect on the fowl, the egg production and other functions of the fowl 55

being normal. Moreover, the colored eye pieces do not prevent or hinder the fowl in their search for food nor does the mask prevent the free use of the beak for feather cleaning.

5 It is to be understood that the foregoing detailed description is given merely by way of illustration and that many variations may be made therein without departing from the spirit of this invention.

10 Having described my invention, what I claim as new and desire to secure by Letters Patent is:

A device of the character described, comprising

a member adapted to rest on the beak of a fowl, a pin for holding said member in position on the beak, eye pieces, having transparent colored material, integral with said member and a projection on said member, the construction and arrangement of said projection being such that when it makes contact with a surface it causes said member to pivot about said pin raising said member and simultaneously lowering the eye pieces out of the vision of the fowl.
